Primary Examiner — Catherine Tuttle(74) *Attorney, Agent, or Firm* — Stiennon & Stiennon**CLAIM**

The ornamental design for a floating water pong table, as shown and described.

DESCRIPTION

FIG. 1 is a top plan view of the floating water pong table showing my new design

FIG. 2 is a right side elevational view thereof, the side opposite being a mirror image thereof;

FIG. 3 is a bottom plan view thereof;

FIG. 4 is a front end view thereof, the side opposite being a mirror image thereof; and,

FIG. 5 is an isometric view thereof.

The broken lines shown in FIGS. 1 and 5 are included for the purpose of illustrating features of the floating water pong table and associated elements that form no part of the claimed design.

1 Claim, 2 Drawing Sheets(56)
